(57) **CLAIM**

The ornamental design for a rectangle multi-LED spider marker light for vehicle, as shown and described.

DESCRIPTION

FIG. 1 is a perspective view of my invention of a new ornamental design of a rectangle multi-light emitting diodes (LEDs) "spider" marker light for vehicle;

FIG. 2 is a top view of my new ornamental design shown in FIG. 1;

FIG. 3 is a bottom view of my new ornamental design shown in FIG. 1;

FIG. 4 is a front elevation view of my new ornamental design shown in FIG. 1, the opposite back elevation view being identical; and,

FIG. 5 is a right end elevation view of my new ornamental design shown in FIG. 1, the opposite left end elevation view being identical.
